UNITED STATES PATENT OFFICE.

GEORGE H. WILLARD, OF HOPEDALE, MASSACHUSETTS, ASSIGNOR TO DRAPER CORPORATION, OF HOPEDALE, MASSACHUSETTS, A CORPORATION OF MAINE.

AUTOMATICALLY-THREADING SHUTTLE FOR LOOMS.

Application filed March 31, 1925. Serial No. 19,601.

To all whom it may concern:

Be it known that I, GEORGE H. WILLARD, a citizen of the United States, and a resident of Hopedale, in the county of Worcester and State of Massachusetts, have invented an Improvement in Automatically-
10 Threading Shuttles for Looms, of which the following description, in connection with the accompanying drawings, is a specification, like characters on the drawings representing like parts.

This invention relates to automatically threading shuttles used in looms wherein the weft or filling thread is automatically replenished from time to time, and is more particularly a further development of the automatically threading loom shuttle shown and described in the patent to Edward S. Stimpson, No. 1,483,492, February 12, 1924.

20 In the automatically threading shuttle of the Stimpson patent, a thread casting and guiding device is shown in the thread passage, the top portion of which is unobstructed, so that upon the formation of a
25 loop or overthrow when the shuttle is brought to rest, the shuttle may become wholly unthreaded, that is, the thread may not only be cast upwardly out of the open top of the thread passage throughout its
30 length, but it may also be thrown out of the side delivery eye. This type of shuttle has been found in practice to be effective and advantageous in use. In some cases, however, it is desirable to prevent complete
35 unthreading of the shuttle by the thread casting device while yet permitting partial unthreading, and the present invention therefore provides means at the forward end of the open thread passage to prevent complete unthreading, while permitting partial
40 unthreading of the shuttle.

Under some weaving conditions, as, for instance, in the use of fluffy or loose yarn, the side delivery eye or the passage leading
45 thereto under the thread director may become clogged, and should the shuttle be wholly unthreaded, such may prevent the ready passage of the thread back into the side delivery eye, so, in accordance with the
50 present invention, an automatically threading shuttle is provided with a side delivery eye and a longitudinally extending thread passage having an open top rearward of the side delivery eye, in which portion of the
55 threading slot is a thread casting device for

casting the thread upwardly through the open top of the thread passage on the occurrence of a loop or overthrow, and at the forward end of the thread passage means is provided to prevent complete unthreading of the shuttle.

The various features and new combination of parts constituting the present invention will best be made clear from the following description and the accompanying drawings of one good form thereof.

In the drawings:

Fig. 1 is a perspective view of the front end portion of a shuttle provided with the present invention;

Fig. 2 is an enlarged perspective view of a threading block containing the invention;

Fig. 3 is an end view of the threading block looking from the rear towards the front of the shuttle, or, in other words, from the bobbin chamber frontwardly; and

Fig. 4 is a transverse section of a shuttle containing the present invention and looking towards the forward end thereof.

The shuttle 1 has the usual bobbin chamber 2 in which is mounted the bobbin 3 carrying the filling, and as shown, the shuttle has a bottom opening for the ejection of the filling carrier or bobbin when filling is to be changed.

Frontward of the bobbin chamber is the threading block receiving chamber 4 in which is mounted the threading block of the present invention.

The threading block 5 is provided with a longitudinally extending thread passage 6 which communicates with the side delivery eye 7, and rearward of the side delivery eye where it communicates with the longitudinal thread passage is the thread casting 90 and guiding device 8. The term "rearward" is herein employed as designating that portion of the structure adjacent the bobbin chamber, and consequently the word "frontward" means, of course, that part of the 100 structure nearer the end of the shuttle.

As indicated in Figs. 1 and 2, it will be noted that the longitudinally extending thread passage 6 between the side delivery eye and the bobbin chamber has an unobstructed top opening, and in this portion of the threading block, as shown, is located the thread casting and guiding device 8 which consists of a scroll having a base portion 9 secured to the threading block, and rising 110

therefrom at a point adjacent the bobbin chamber the scroll has an upwardly, frontwardly and laterally extending thread casting portion 10, the construction being such as more fully described in the Stimpson patent, that upon the occurrence of a loop or overthrow as the shuttle is brought to rest at the end of its flight, the thread casting device will act upon the thread to throw it upwardly out of the thread passage and from the control of the thread casting and guiding device.

10 The thread block 5 is shown as provided with an opening 11 through which may pass the screw 12 for screwing the threading block in place in the shuttle.

15 The thread casting and guiding device 8 has its end portion 13 extending frontwardly in the thread passage, and where the thread casting and guiding device is formed as a scroll, as herein shown, the end portion 13 of the scroll extends frontwardly in the thread passage to a point rearward of a bridge 14 extending transversely of the thread passage. During normal weaving the thread *a* from the bobbin 3 passes through the thread casting and guiding device 8, over the bridge 14 and then laterally through the side delivery eye. The thread 20 supporting surface of the bridge 14 is shown rounded between the side walls of the thread passage, and such form of bridge is desirable in order to centralize the thread as it is delivered from the bobbin through the 25 thread passage and side delivery eye.

30 With the exception of the particular form of the bridge, the parts so far described may be substantially the same as the corresponding parts in the Stimpson patent above mentioned.

35 At one side of the longitudinally extending thread passage adjacent the side delivery eye is the thread director 15 which may likewise be of the same general construction as that in the Stimpson patent, and between the edge portion 16 of the thread director and the wood of the shuttle a passageway is formed for the entrance of the thread into the side delivery eye.

40 The opposite side of the thread passage is provided with a guard 17 which may be constituted conveniently by a side wall portion of the threading block 5, as indicated in Fig. 2. The guard 17 overhangs the end portion of the thread director 15 and provides means for intercepting the thread when a loop occurs and the thread casting and guiding device casts the thread upwardly out of the thread passage. Such interception of the thread by the guard 17 and thread director prevents complete unthreading of the shuttle; that is, these parts co-act to prevent the thread from being thrown out of the side delivery eye, yet do not interfere with the operation of

the thread casting device in casting or throwing the thread upwardly out of the longitudinally extending thread passage rearward of the side delivery eye.

45 From the construction described as an embodiment of the present invention, it will be noted that the shuttle has a thread casting device in the longitudinally extending thread passage and a side delivery eye, and that between the side delivery eye and the rear portion of the thread passage is located the thread casting and guiding device, in effect at or below the unobstructed top opening of the thread passage, while frontward of the side delivery eye, means is provided to prevent complete unthreading of the shuttle when the thread casting and guiding device throws the loop of thread upwardly out of the thread passage. By thus obstructing the complete unthreading of the 50 shuttle, while permitting partial unthreading thereof on the occurrence of a loop or overthrow, all liability of the shuttle failing to be completely threaded owing to an accumulation of lint in the side delivery eye is 55 overcome.

60 The present improvement, therefore, consists in a further development of the automatically threading shuttle disclosed in the Stimpson patent hereinbefore mentioned, in 55 that the present invention permits partial unthreading of the shuttle upon the occurrence of a loop or overthrow, but prevents complete unthreading of the shuttle.

65 What is claimed is:

1. An automatically threading loom shuttle having an open top thread passage delivery eye communicating with the thread passage, a thread casting and guiding device in the thread passage constructed and arranged to cast the thread upwardly and out of the thread passage on the occurrence of an overthrow of the thread as the shuttle is arrested at the end of its flight, and means at the forward end 105 of the thread passage for intercepting the loop, or overthrow of thread to prevent complete unthreading of the shuttle.

110 2. An automatically threading loom shuttle having a longitudinally extending thread passage open at its top for the free exit of the thread and side delivery eye, a thread casting scroll having a portion extending upwardly, laterally, and frontwardly starting from a point adjacent the bobbin chamber for casting the thread upwardly from and out of the thread passage on the occurrence of a loop or overthrow, and a guard at the forward end of the thread passage for intercepting the loop or overthrow of thread 115 to prevent complete unthreading of the shuttle.

120 3. An automatically threading loom shuttle having a side delivery eye, and a threading block provided with a longitudinally 125

- extending thread passage having an open top rearward of the side delivery eye, a thread casting and guiding device in the thread passage rearward of the side delivery eye for casting the thread upwardly through the open top of the thread passage on the occurrence of a loop or overthrow, and a guard frontward of the side delivery eye to engage the loop or overthrow of thread and prevent complete unthreading of the shuttle. 5
4. An automatically threading loom shuttle having a side delivery eye, a threading block provided with a longitudinally extending thread passage open at its top rearward of the side delivery eye, a thread casting and guiding device in the thread passage rearward of the side delivery eye for casting the thread upwardly through the open top of the thread passage on the occurrence of a loop or overthrow, and a thread director and overhanging guard 15 frontward of the thread casting and guiding device to intercept the loop of thread as it is cast from the thread passage and the shuttle is partially unthreaded to prevent complete unthreading of the shuttle. 20
- it is cast from the thread passage to prevent complete unthreading of the shuttle. 25
5. An automatically threading loom shuttle having a side delivery eye, a threading block provided with a longitudinally extending thread passage open at its top rearward of the side delivery eye, a thread casting and guiding device in the thread passage rearward of the side delivery eye for casting the thread upwardly through the open top of the thread passage on the occurrence of a loop or overthrow, and a thread director and overhanging guard 30 frontward of the thread casting and guiding device to intercept the loop of thread as it is cast from the thread passage and the shuttle is partially unthreaded to prevent complete unthreading of the shuttle. 35
- 40

In testimony whereof, I have signed my name to this specification.

GEORGE H. WILLARD.
